Primary Examiner — Susan Bennett Hattan*Assistant Examiner* — Leanne Was(74) *Attorney, Agent, or Firm* — Jura C. Zibas; Gregory N. Brescia; Wilson, Elser, Moskowitz, Edelman & Dicker, LLP.(57) **CLAIM**

An ornamental design for a cosmetic bottle, as shown and described.

DESCRIPTION

FIG. 1 is a perspective view of a cosmetic bottle showing the new design;

FIG. 2 is a bottom rear perspective view of a cosmetic bottle shown in FIG. 1;

FIG. 3 a front view for the cosmetic bottle shown in FIG. 1, the opposite side being a mirror image thereof;

FIG. 4 is a side view for the cosmetic bottle shown in FIG. 1, the opposite side being a mirror image thereof;

FIG. 5 is a top view for the cosmetic bottle shown in FIG. 1; and,

FIG. 6 is a bottom view for the cosmetic bottle shown in FIG. 1.

The broken lines in the drawings depict portions of the cosmetic bottle that form no part of the claimed design.

1 Claim, 5 Drawing Sheets(56)
